(57) **CLAIM**

The ornamental design for a fishing reel body, as shown and described herein.

DESCRIPTION

FIG. 1 is a front, left perspective view of a fishing reel body showing the new design;

FIG. 2 is a front, right perspective view of the fishing reel body of FIG. 1 showing the new design;

FIG. 3 is a front, bottom, left side perspective view of the fishing reel body of FIG. 1 showing the new design;

FIG. 4 is a front view of the fishing reel body of FIG. 1 showing the new design;

FIG. 5 is a rear view of the fishing reel body of FIG. 1 showing the new design;

FIG. 6 is a top view of the fishing reel body of FIG. 1 showing the new design;

FIG. 7 is a bottom view of the fishing reel body of FIG. 1 showing the new design;

FIG. 8 is a right side view of the fishing reel body of FIG. 1 showing the new design; and,

FIG. 9 is a left side view of the fishing reel body of FIG. 1 showing the new design.

The broken lines depict portions of the fishing reel body that form no part of the claimed design.
